(57) **CLAIM**

The ornamental design for a stroller wagon canopy as shown and described.

DESCRIPTION

FIG. 1 is a top perspective view showing the front, left, and top sides of a stroller wagon canopy in its environment; FIG. 2 is a top perspective view showing the front, left, and top sides of the stroller wagon canopy;

FIG. 3 is a left side elevation view of the stroller wagon canopy;

FIG. 4 is a right side elevation view of the stroller wagon canopy;

FIG. 5 is a front elevation view of the stroller wagon canopy;

FIG. 6 is a rear elevation view of the stroller wagon canopy;

FIG. 7 is a top plan view of the stroller wagon canopy;

FIG. 8 is a bottom plan view of the stroller wagon canopy; and,

FIG. 9 is a top perspective view showing the front, left, and top sides of the stroller wagon canopy with all screen flaps lowered.

The portions shown in broken lines define environmental structure that are elements related to the claimed design and form no part of the claimed design.
